CLAMPING APPARATUS

Joseph "S" Martinek, San Diego, Calif.

Application April 14, 1939, Serial No. 267,864

7 Claims. (Cl. 294—85)

My invention relates to an adjustable clamping apparatus to be used for a variety of purposes, and the objects of my invention are:

First, to provide a clamping apparatus of this class for supporting exercising bars, swings or the like in a doorway;

Second, to provide a clamping apparatus of this class for use in supporting scaffolding, various sized beams or the like;

Third, to provide a clamping apparatus of this class which may be used as a connecting means for towing automobiles;

Fourth, to provide a clamping apparatus of this class which is adjustable to objects of various shapes and sizes;

Fifth, to provide a clamping apparatus of this class which might be used for the purpose of removing automobile wheels;

Sixth, to provide a clamping apparatus of this class which may be constructed of opposing members of the same pattern; and

Seventh, to provide a clamping apparatus of this class which is very simple and economical of construction, efficient in its action and will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a side elevational view of my adjustable clamping apparatus; Fig. 2 is an edge elevational view of my adjusting clamping apparatus; and Fig. 3 is a side elevational view of two of my adjustable clamps supporting an exercising bar shown fragmentarily, shown clamped to the upper members of a door sill.

Similar characters of reference refer to similar parts and portions throughout the several views of the drawing:

The clamp members 1, 2, 3 and 4, chain 5, adjusting bolts 6, 7, 8, 9, 10 and 11 and the clamp connection link 12 constitute the principal parts of my invention.

It will be here noted that the clamp members 1 and 2 are made in duplicate. Also the clamp members 3 and 4 are made in duplicate. The clamp members 1 and 2 are provided with adjusting holes 1a and 2a to correspond with the adjusting holes 3a and 4a respectively in the clamp members 3 and 4. Adjustment is made by

means of the holes 1a, 2a, 3a, and 4a. The bolts 6 and 7 are tightened by their respective wing nuts 6a and 7a, which bolts are inserted through the adjusting holes 1a and 3a and 2a and 4a respectively. The clamp members 1 and 2 are also provided with sharp hook portions 1b and 2b respectively. The clamp members 1 and 2 are provided with outwardly protruding ridge portions 1c and 2c extending the full length of the clamp members 1 and 2. These portions 1c and 2c are made to fit and correspond with the channels 3d and 4d in the clamp members 3 and 4 as shown best in Figs. 1 and 2 of the drawing.

The clamp members 3 and 4 are provided with adjusting holes 3a and 4a to correspond with the adjusting holes 1a and 2a respectively of the clamp members 1 and 2. The clamp members 3 and 4 are provided with adjusting holes 3b and 4b which are fastened and tightened by the wing nuts 10a and 10b and their respective threaded counterparts 10c and 10d of the bolt 10. The clamp members 3 and 4 are also provided with lug portions 3c and 4c respectively through which are inserted the threaded bolts 8 and 9 of the chain hooks 8a and 9a respectively between which the chain 5 is suspended, as shown best in Fig. 1 of the drawing.

It will be here noted that the clamp members 3 and 4 are provided with angularly extending portions 3e and 4e which are adapted to cross each other as shown best in Fig. 1 of the drawing and in which the bolt 10 is mounted. The portion 10e of the bolt 10 is integral with the threaded portions 10c and 10d and that the portion 10e is internally threaded to receive the 35 threaded adjusting bolt 11, which threaded adjusting bolt 11 is provided with outwardly extending pin portions 11a which are for the purpose of facilitating the turning of the threaded adjusting bolt 11 in the bolt portion 10e.

The clamp connection link 12 surrounds the portion 10e and hangs downwardly therefrom as shown best in Figs. 1 and 2 of the drawing.

The operation of my clamping apparatus is substantially as follows: Upon a beam or other object, this clamp may be fastened to support a given object by first adjusting the clamp by means of the adjusting holes 1a, 2a, 3a and 4a to make it fit the particular thickness of said beam or other object. By means of the chain 5, the 50 relative spaced relation of the clamp members 1 and 2 may be accomplished to fit the width of said beam or object. If closer adjustment of this relation is required, the wing nuts 8b and 9b are tightened or loosened as desired. As the hook 65

portions 1b and 2b are hooked over the top of the beam or other object in opposed relation to each other, the upper end of the adjusting bolt 11 is tightened against the lower surface of said beam or object and works in combination with the chain 5 to accomplish a firm fastening of the entire clamp. The load may then be applied to the clamp by means of the clamp connection link 12. The clamp may be applied to the bumper of an automobile in the same manner as herein described for the purpose of towing said automobile.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a clamping apparatus of the class described, a pair of substantially duplicate clamp members each consisting of two longitudinally shiftable members and each provided with extended hook portions on one end and with angularly turned portions at their opposite ends, means for connecting said angular portions together in adjustable relation to each other.

2. In a clamping apparatus of the class described, a pair of substantially duplicate clamp members each consisting of two longitudinally shiftable members and each provided with extended hook portions on one end and with angularly turned portions at their opposite ends, means for connecting said angular portions together in adjustable relation to each other, and an adjusting bolt adjustably mounted in said connecting means and extending upwardly toward said hook portions.

3. In a clamping apparatus of the class described, a pair of substantially duplicate clamp members each provided with extended hook portions on one end and with angularly turned portions at their opposite ends, means for connecting said angular portions together in adjustable relation to each other, an adjusting bolt adjustably mounted in said connecting means and extending upwardly toward said hook portions, and non-yieldable means connecting said clamp members intermediate their ends.

4. In a clamping apparatus of the class described, a pair of substantially duplicate clamp members each provided with extended hook portions on one end and with angularly turned portions at their opposite ends, means for connecting said angular portions together in adjustable relation to each other, an adjusting bolt adjustably mounted in said connecting means and extending upwardly toward said hook portions, non-yieldable means connecting said clamp members intermediate their ends, and means for adjusting said connecting means.

5. In a clamping apparatus of the class described, a pair of substantially duplicate clamp members, means for lengthening or shortening said clamp members, each of said clamp members provided with hooks on their one extended ends and provided with angular portions at their opposite ends, and chain and hook means connecting said clamp members intermediate their ends, clamp bolt means connecting said clamp members at their angular portions in spaced relation to each other.

6. In a clamping apparatus of the class described, a pair of substantially duplicate clamp members, means for lengthening or shortening said clamp members, each of said clamp members provided with hooks on their one extended ends and provided with angular portions at their opposite ends, chain and hook means connecting said clamp members intermediate their ends, clamp bolt means connecting said clamp members at their angular portions in spaced relation to each other, and an adjusting bolt screw threaded in said clamp bolt with its end extending upwardly between said clamp members toward said hook portions.

7. In a clamping apparatus of the class described, a pair of substantially duplicate clamp members, means for lengthening or shortening said clamp members, each of said clamp members provided with hooks on their one extended ends and provided with angular portions at their opposite ends, chain and hook means connecting said clamp members intermediate their ends, clamp bolt means connecting said clamp members at their angular portions in spaced relation to each other, an adjusting bolt screw threaded in said clamp bolt with its end extending upwardly between said clamp members toward said hook portions, and a link supported on said clamp bolt in said angular portions.

JOSEPH "S" MARTINEK.
